UNITED STATES PATENT OFFICE.

HARRY LEE, OF LIVINGSTON, MONTANA.

SELF-DISCHARGING TRAY.

1,384,667.

Specification of Letters Patent. Patented July 12, 1921.

Application filed April 9, 1920. Serial No. 372,520.

To all whom it may concern:

Be it known that I, HARRY LEE, a citizen of the United States, residing at Livingston, in the county of Park and State of Montana, have invented certain new and useful Improvements in Self-Discharging Trays; and I do hereby declare the following to be a full, clear, and exact description of the invention, such as will enable others skilled in the art to which it appertains to make and use the same.

The object of the invention is to provide a tray suitable for the use of waiters in hotels, restaurants or the like whereby the dishes may be transported to and deposited upon the dining table and subsequently engaged and removed from the same without independently or individually handling the dishes, and furthermore to the end that a tray may readily be carried in each hand so that if desired two tables may be served on one trip, the deposit of the dishes carried by each tray being effected in one operation, and with these objects in view the invention consists in a construction, combination and arrangement of parts of which a typical embodiment is illustrated in the accompanying drawing, wherein:

Figure 1 is a plan view of the tray.
Fig. 2 is a side view of the same partly in section.

Fig. 3 is a sectional view of the operating mechanism on an enlarged scale.

Fig. 4 is a transverse sectional view on the plane indicated by the line 4-4 of Fig. 2.

The apparatus consists essentially of a main supporting frame having the marginal bars 10 and longitudinal and transversely intersecting filler bars 11 and 12 suitably secured together and to the marginal bars at the points of intersection to insure the necessary rigidity, and thereby forming within the space bounded by the marginal bars a plurality of divisional spaces or units of which any desired number may be provided, a plurality of dish or receptacle engaging clamps located in said divisional spaces or units of the main frame and formed by intersecting longitudinal and transverse rods 13 and 14 arranged in longitudinal and transverse pairs, and operating mechanism connected with said rods whereby the members of each pair may be moved toward and from each other in a direction at right angles to that of the intersecting pair of rods.

The portions of the marginal bars at the

angles of the frame, and at any other suitable points may be extended to form downwardly projecting feet or rests 15 to the end that when the apparatus is standing upon a table or flat surface the terminal eyes 16 of the movable rods forming the clamping members and which are slidably mounted upon said marginal and filler bars at the point of intersection therewith may move freely and without frictional contact with said supporting surface. The clamping rods are preferably flat as indicated as affording greater stiffness and strength without unduly increasing the weight of the structure.

The portions of the clamping rods which form the dish engaging jaws as indicated at 13^a and 14^a may be outwardly curved or inwardly concaved as indicated or may be provided with any other suitable form to present jaws which will effectively engage and hold a plate or dish of the desired size. Obviously in this particular the mechanism is susceptible of wide variation, and in the construction illustrated the side clamping units indicated respectively at 17 and 18 are of elongated form suitable for the reception of platters or large dishes as compared with those which may properly be engaged by the other clamping units of the device.

The corresponding longitudinal clamping lugs or in other words those longitudinal clamping rods which are arranged at the corresponding sides of the dish receiving spaces are connected for simultaneous movement by transverse tie rods 19, and similarly the corresponding transverse clamping rods are connected for simultaneous movement in a common direction by the longitudinal tie rods 20, and within the central space or unit of the main or supporting frame which for convenience is occupied by the operating mechanism, connection is made with the longitudinal and transverse clamping rods which intersect said space or units, so that when the transverse clamping rods thereof are drawn toward each other and correspondingly the longitudinal clamping rods are drawn toward each other, the dish receiving spaces throughout the structure will be contracted to engage dishes located respectively therein, whereas an opposite movement of said longitudinal and transverse rods or the portions thereof which intersect the central space or unit of the plane will result in a spreading of the dish

receiving spaces throughout the structure, to release such dishes as may have been engaged by the clamping jaws.

The mechanism employed for operating these rods as illustrated in the drawing consists of a plunger 21 provided at its upper end with a handle or grip 22 and mounted for sliding movement in guides 23 and 24, suitably spaced and held in rigid relation by stays or braces 25 which may as shown extend from the angles of the central space or unit of the supporting frame, extensions 26 of said stay rods being carried downward through said guides which may as indicated be in the form of rings or spiders to form guides upon which is mounted a disk or head 27 connected by links 28 with the inner arms of bell crank levers 29 of which the outer arms are in turn connected by links 30 with said longitudinal and transverse clamping rods. The bell crank levers are mounted upon a fulcrum ring 31 supported by the diagonal braces or stay rods 25 and the lower extremities of the extensions 26 of said stay rods, below the plane of the head or disk 27 may be carried radially to form transverse braces attached to the body portions of the stay rods. Obviously this arrangement of bracing and supporting elements may be varied, with due regard to the primary purpose of affording a substantial support for the plunger and the devices connected therewith, and such a connection between the same and the main or supporting frame as to permit of the efficient carrying of the tray thereby.

Interposed between a collar 32 on the plunger and the lower guide 24 is a coiled spring 33 serving to yieldingly hold the plunger elevated and hence the clamp of the tray closed, although obviously when the tray is being carried by the grip or handle 22 the strain upon the plunger will serve to maintain the clamping members in their dish engaging relation.

The plunger is also preferably provided with webs 34 operating in notches 35 in the upper guide disk 23, and when the plunger has been depressed, in opposition to the tension of the spring 33 to open the clamp of the tray, the turning of the grip or handle and hence of the plunger rod will serve to move said ribs out of alinement with the notches and lock the plunger in a depressed position and hence the clamping rods in their separated relation. Hence when a load of dishes has been transported to the dining table and the apparatus has been deposited thereon, it is simply necessary for the operator to depress the plunger and turn it slightly whereupon the tray may be lifted freely from the dishes which will be left standing in proper position upon the table. Similarly when it is desired to engage the dishes to remove them from the table, the

plunger may be locked in its depressed position with the clamps opened, and after the apparatus has been positioned with the various clamps in engaging relation with the dishes, the plunger may be released to permit the upward movement thereof and hence the closing of the clamps to lock the dishes in place in the tray. The latter may then be released by means of the grip or handle and removed to the kitchen or the side table.

It will be noted that the space above the plane of the body of the tray, except of course that portion occupied by the operating mechanism, is entirely open and unobstructed, so that plates or similar dishes in a stack may be carried by a single clamping unit, and therefore provision is made for great economy in the handling of dishes both in transporting the same to and from the point of use and in releasing and engaging the same as the conditions may require.

What is claimed is:—

1. A serving tray having a main or supporting frame, pairs of clamping rods arranged in intersecting relation, the members of each pair being movable toward and from each other in a direction at right angles to that of the intersecting pair, and means for actuating said clamping rods.

2. A serving tray having a main or supporting frame, longitudinal and transverse clamping rods arranged in pairs, the members of each pair being movable toward and from each other in a direction at right angles to the members of the intersecting pair, and the corresponding members of different pairs being connected in series for simultaneous movement in a common direction, and operating means for communicating simultaneous movement to the several sets of clamping rods for effecting mutual opening and closing movement of the coöperating portions of said longitudinal and transverse pairs.

3. A serving tray having a main or supporting frame, longitudinal and transverse intersecting pairs of clamping rods connected in series for mutual dish engaging and releasing movement, guiding means supported by and connected with the said main or supporting frame, a plunger mounted in said guiding means and having a terminal tray carrying grip or handle, and connections between said plunger and the clamping rods.

4. A serving tray having a main or supporting frame, longitudinal and transverse intersecting pairs of clamping rods connected in series for mutual dish engaging and releasing movement, guiding means supported by and connected with the said main or supporting frame, a plunger mounted in said guiding means and having a terminal tray carrying grip or handle, connections

between said plunger and the clamping rods, said rods being moved into their dish engaging relation by an upward movement of said plunger rod.

- 5 5. A serving tray having a main or supporting frame, longitudinal and transverse intersecting pairs of clamping rods connected in series for mutual dish engaging and releasing movement, guiding means supported by and connected with the said main or supporting frame, a plunger mounted in said guards and having a terminal tray carrying grip or handle, connections between said plunger and the clamping rods,
- 10 15 said rods being moved into their dish engaging relation by an upward movement of said plunger rod, and means for rocking the plunger in a position to maintain the clamping rods in their dish releasing relation.
- 20 6. A serving tray having a main or supporting frame, longitudinal and transverse intersecting pairs of clamping rods connected in series for mutual dish engaging and releasing movement, guiding means supported by and connected with the said main or supporting frame, a plunger mounted in said guards and having a terminal tray carrying grip or handle, connections between said plunger and the clamping rods, said rods being moved into their dish engaging relation by an upward movement of said plunger rod, and means for rocking the plunger in a position to maintain the clamping rods in their dish releasing relation, said
- 25 30 35

plunger being revoluble and having longitudinal guiding webs operating in guide notches and adapted for disalignment therewith to secure the plunger with the clamping rods in their dish releasing relation. 40

7. A serving tray having a main or supporting frame, longitudinal and transverse intersecting pairs of clamping rods connected in series for mutual dish engaging and releasing movement, guiding means supported by and connected with the said main or supporting frame, a plunger mounted in said guards and having a terminal tray carrying grip or handle, connections between said plunger and the clamping rods, said rods being moved into their dish engaging relation by an upward movement of said plunger rod, and means for rocking the plunger in a position to maintain the clamping rods in their dish releasing relation, said plunger being 50 revoluble and having longitudinal guiding webs operating in guide notches and adapted for disalignment therewith to secure the plunger with the clamping rods in their dish releasing relation, the same consisting 55 of bell crank levers having terminal connections respectively with the adjacent clamping rods and the plunger.

In testimony whereof I affix my signature in presence of two witnesses.

HARRY LEE.
